DESIGN FOR A PLATE OR SIMILAR ARTICLE

Victor Skellern, Fenton, Stoke-on-Trent, England, and John Edward Goodwin, Penrhyn Bay, Llandudno, North Wales, assignors to Josiah Wedgwood & Sons, Inc. of America, New York, N. Y., a corporation of New York

Application May 14, 1940, Serial No. 92,352

Term of patent 7 years

To all whom it may concern:

Be it known that we, Victor Skellern, residing at 14 Maud Street, Fenton, Stoke-on-Trent, England, and John Edward Goodwin, residing at Etruria, St. David's Road, Penrhyn Bay, Llandudno, N. Wales, British Isles, both subjects of Great Britain, have invented a new, original, and ornamental Design for a Plate or Similar Article, of which the following is a specification, reference being had to the accompanying drawing, forming part thereof.

The drawing is a plan view of a plate showing our new design, part of the border decoration being indicated in dotted lines, but it being understood that the border decoration is continued around the border of the article.

We claim:

The ornamental design for a plate or similar article, substantially as shown and described.

VICTOR SKELLERN.
JOHN EDWARD GOODWIN.
